CLAIM

The ornamental design for a bottle retaining support rack, as shown and described.

DESCRIPTION

FIG. 1 is a perspective view of one embodiment of the bottle retaining support rack embodying my new design;

FIG. 2 is a front elevational view of the unit of FIG. 1; FIG. 3 is a side elevational view taken from the right side of FIG. 2;

FIG. 4 is a rear elevational view of the unit;

FIG. 5 is a top plan view of the unit;

FIG. 6 is a perspective view of a modified embodiment of my new design;

FIG. 7 is a front elevational view of the unit of FIG. 6; and

FIG. 8 is a side elevational view of the unit of FIGS. 6 and 7 taken from the right side of FIG. 7.

FIG. 6

FIG. 7

FIG. 8

FIG. 5

FIG. 4

FIG. 1

FIG. 2

FIG. 3
